UNITED STATES PATENT OFFICE

WALTER B. IVEY, OF SOUTH JACKSONVILLE, FLORIDA

SPRINKLER NOZZLE

Application filed December 3, 1931. Serial No. 578,808.

This invention relates to new and useful improvements in water sprinkler nozzles and its object is to provide an improved sprinkler nozzle which due to its construction will offer little resistance to water and will insure an even distribution of water. 55

Another object is to provide a sprinkler nozzle which is simple in construction and easily adjusted from a light spray to heavy 10 drops and one which may be manipulated to project water in half spraying circle when desired.

Referring to the accompanying drawing, which is made a part hereof and on which 15 similar reference characters indicate similar parts,

Figure 1 is a sectional view in elevation showing the improved sprinkler nozzle,

Figure 2, a perspective view of the distributor head which is used to produce a 20 complete spraying circle,

Figure 3, a perspective view of the distributor head which is used to produce a half spraying circle, and

Figure 4, a modified form of the sprinkler nozzle.

In the drawing reference character 10 indicates the casing of the sprinkler nozzle, the upper portion 11 being reduced in size 30 and provided with threads 12 on its interior surface. A deflecting element 13 comprising a plate 14 and a depending portion 15 is secured to the casing by means of threads 16 on the portion 15. Instead of having the element 13 and the casing 10 of separate parts it may be desired to form these parts of a single casting which would reduce the cost of manufacture considerably. The deflecting element 13 is further provided 35 with a bore 17 in communication with the interior of the casing 10. The center of plate 14 is provided with a cone-shaped depression 18 and a flat rim 19 on its upper side.

The lower portion of the casing 10 has a narrow cross member 20 formed on its interior and extending across the center thereof serving as a support for screw-threaded bolt 21 which extends upwardly 45 through the bore 17 and on which the dis-

tributor heads 22 and 23 are threaded. The bolt 21 is threaded through member 20 and is held in fixed position by a nut 24 resting against the lower side of the member 20. The bolt 21 is small enough to allow water 55 to flow through the bore 17.

The distributor head 22 is provided with a cone-shaped depression 25 in one end and a flat surface 26 on the other. The head 23 is similar in construction to the head 60 22 and is further provided with a cut down edge indicated at 27 and extending a distance equal to one-half the circumference of the head for a use which will later be described. 65

The casing 10 may be secured to a supply line by the threads 28 formed on the interior surface below the member 20.

Figure 4 is a modified form of the improved sprinkler nozzle which is adapted 70 to be attached to a garden hose or the like and held in position by a support driven in the ground.

This form comprises a casing 28 having a deflecting plate formed integrally on its 75 upper end and similar to that shown in Figure 1 at 14. The casing 28 is provided with a bore extending from the top, downwardly and outwardly through the side. The casing is also threaded at 29 for the 80 hose connection.

A pin or rod 30 threaded on its upper end is turned through the bottom portion of the casing to the limit of its threads making the rod rigid with respect to the casing. The threaded portion of the rod extends sufficiently above the casing to mount the distributor heads 31 and 32. The lower end of the rod is sharpened to permit easy insertion into the ground. 85

The device is shown in assembled position in Figures 1 and 4. To operate the sprinkler, the topmost head which always serves as a lock for the head adjacent the deflecting element is loosened. The lower head is then rotated in either direction until the desired opening is obtained. The upper head is tightened against the lower to hold it in fixed position and a spray from a light mist to very heavy drops can be produced de- 90 95 100

pending on the position of the lower head with respect to the deflecting element.

The angle of the depression in the deflecting element offers least resistance to water when thrown against the wind and therefore produces a more uniform spray than is obtained in other types of sprinklers. The flat rim on the plate tends to produce an even distribution of water. The concaved head forms a convex ring of water which is forced against the deflecting plate causing even distribution of water and tends to increase the area covered by the spray circle. In using a flat end head as is usually the case the water is thrown in a manner similar to a stream from a hose as it strikes a flat surface; the water is deflected in a very irregular manner. The structure described overcomes such a condition and the results produced are quite an improvement over other sprinkler nozzles.

By simply reversing and interchanging the heads 22 and 23 a half spraying circle is produced. The edge of the cone-shaped depression in the head 23 is engaged by the deflecting element leaving an outlet formed by the cut-down edge 27 through which the water is forced producing a half spray circle. In this case the head 22 serves as a lock for the head 23.

In the above described sprinkler head it is clearly seen that a device results by which water may be projected in a variety of forms varying from a fine mist to heavy drops and so constructed that it is also possible to produce a half circle spray when desired.

It will be obvious to those skilled in the art that various changes may be made in my device without departing from the spirit of the invention and therefore I do not limit myself to what is shown in the drawing and described in the specification, but only as indicated by the appended claims.

Having thus fully described my said invention, what I claim as new and desire to secure by Letters Patent, is:

1. A spray nozzle comprising a casing, a deflecting element mounted on said casing, the upper surface of said element having a cone-shaped depression therein and an axial bore in communication with said casing, a support mounted in said casing having a rod adjustably secured therein, said rod extending upwardly through said bore, a pair of interchangeable and reversible adjustable heads mounted on said rod, each head being flat on one end and having a cone-shaped depression in the other, part of the edge of the cone-shaped depression of one head being reduced to provide an opening when said head is positioned in contact with said deflecting element, the upper head serving as a lock nut for the lower head when the flat surface ends are positioned to contact one another, substantially as set forth.

2. In a spray nozzle, a casing having inlet and outlet openings therein, a deflecting element mounted on said casing, the upper surface of said element having a cone-shaped depression therein and an axial bore in communication with the outlet opening of said casing, a rod secured in said casing extending through the outlet opening thereof, a pair of interchangeable and reversible distributor heads mounted on said rod, each head being flat on one end and having a cone-shaped depression on the other, part of the edge of the cone-shaped depression of one head being cut away to provide an opening when said head is positioned in contact with said casing for producing a variation of sprays, substantially as set forth.

In witness whereof, I have hereunto set my hand at South Jacksonville, Florida this 4th day of November, A. D. nineteen hundred and thirty-one.

WALTER B. IVEY.
